E. H. THOMPSON

SAFETY SWITCH

Filed May 20, 1922

Inventor:
Ernest H. Thompson
by
Geo. N. Goldmark,
atty.

UNITED STATES PATENT OFFICE.

ERNEST H. THOMPSON, OF EVANSTON, ILLINOIS.

SAFETY SWITCH.

Application filed May 20, 1922. Serial No. 562,277.

To all whom it may concern:

Be it known that I, ERNEST H. THOMPSON, a citizen of the United States, and resident of Evanston, in the county of Cook and State of Illinois, have invented certain new and useful Improvements in Safety Switches, of which the following is a specification.

This invention relates to electric snap switches such as are placed on the wall or other convenient locality adjacent to a door-way in a closet or stairway where it is desired to turn on and turn off the switch which controls the lighting when one enters or leaves the room or passage.

It is a matter of very frequent occurrence that when the light switch has been turned on the one leaving the room will forget to turn off the switch, and as this oversight is induced by reason of the door being closed the lights in that circuit may continue to function for many hours or days in some cases without discovery.

The present invention is intended to prevent any such accidental occurrence by so combining the switch with door-actuated means that when the door is closed the switch is automatically turned off if it has not been turned off manually before the door is closed, the arrangement being such however that if the switch has been turned off before the door is closed, the door-actuated controlling means will not operate to throw the switch from open to closed position.

This and other features of the invention will be particularly described in the following specification and will be defined in the claims hereto annexed.

In the accompanying drawings I have illustrated a simple and convenient form of device for carrying into effect the principles of this invention, in which:

Figure 1 is a side elevation of the complete device arranged in proximity to a door which is shown in section.

Figure 2 is a plan view of the same device, a door and wall being partly shown in section.

Figure 3 is a horizontal central section showing the operative means by which the door-actuated lever actuates the switch mechanism.

Figures 4 and 5 are perspective views showing, respectively, two ratchet members included in the switch actuating mechanism.

Figure 6 is an end elevation showing the two ratchet members in operative relationship.

Figure 7 is a detail view of the lower end of the door-actuated arm illustrating how the pull member or cord is adjustably connected with said arm.

In carrying out the principles of this invention I employ any ordinary type of wall switch operated by a rotatable spindle through the medium of a button or other equivalent gripping means at its outer end. As the precise construction of the wall switch proper forms no part of this invention I have illustrated the principal parts of said switch which are pertinent to this invention without attempting to show all details thereof.

The type of switch illustrated in the drawings comprises a hollow porcelain body member 1, carrying a rotatable spindle 2, by whose rotation the diametrically projecting switch arms 3 are thrown by successive turns, through say a quarter of an arc, into and out of circuit-closing engagement with the electrical terminals one of which is shown at 4. The gripping button or member 3^a secured to the outer or front end of the spindle permits the switch to be readily operated by hand. A casing or lid 13 serves to cover the working parts and is provided with an opening or window 13^a to expose to view the indicator plate on the spindle to show whether the switch is closed or open.

The essence of the invention consists, generally speaking, in combining with a switch of such a type or its equivalent, a ratchet pull mechanism which is so connected or co-ordinated with an actuating arm located to be operated by the door coming into closed position so as to throw the switch from closed to open position but to fail to throw the switch to closed position when it is already open.

The specific mechanism shown for accomplishing this purpose embraces a stud member 7 projected from a supporting plate 7^a and at its outer end provided with a bearing recess to receive the rear end of the switch spindle 2. An annular or recessed base member 6 is secured to the wall and to the forward face of this base member or support. The switch itself is detachably secured in any suitable manner with the rear end of the switch spindle 2 properly pro-

jecting slightly into the bearing recess formed in the front end of the stud 7. On the rear end of the spindle next to this bearing is secured one ratchet member comprising a disk or plate 14 having diametrically opposed peripheral ratchet teeth or cam surfaces 15 each formed with a gradual slope and terminating in an abrupt shoulder.

On the stud 7 is mounted the other ratchet member which comprises a centrally perforated disk or pulley 8, with its periphery grooved to retain a flexible pull member, which in this case is in the form of the usual pull chain 9 one end of which is anchored to the pulley and the other end of which passes out through an opening in the base for adjustable attachment to the pivotal arm 22. A torsion spring 11 is coiled around the stud with one end projecting out to engage or hook against a stop pin 12 on the plate 7*, while the other end of said torsion spring is bent around a rearwardly projecting pin 10 attached to the rear face of the ratchet pulley 8. To the front face of the pulley is secured the ratchet member comprising a plate 16 with diametrically projected inclined teeth or prongs 17 so arranged as to ride over the sloping faces of the cam teeth 15 on ratchet plates 14, when rotated in a counterclockwise direction as indicated by the arrow in Figure 4 by the tension of the torsion spring 11.

On the door-post ledge immediately adjacent to the swinging edge of the door 30 is mounted a plate 20 which carries a screw 21 which serves as a fulcrum for the lever or arm 22 whose upper end may be provided with a roller or knob 23 to be engaged by the door and pushed inwardly as the door closes. The pull or chain member 9 is attached to the lower end of said lever and preferably in such a way as to provide for adjustment to secure the proper action. In this case, as a chain is used the arm is provided with a series of shallow transverse sockets for receiving a series of several adjacent bolts of the chain which are held in place by means of overhanging screw 24.

The lower end of the lever is provided with a shoulder 26, and adjacent thereto is pivoted a latch 27 in position to be hooked against said shoulder and to drop away therefrom when the tension is released. The upper attaching screws of the plate 20 may serve to limit the arc of movement of the arm 22 in either direction or the latch itself may serve as one of these arm-limiting stops.

The operation of the device is as follows. When the door is open the arm 22, under the tension of the pull member 9, caused by the torsion spring 11, will tend to assume a position shown in dotted lines in Figure 1. In this position the diametric ratchet teeth 17, let us assume, lie in the vertical

position as indicated in Figures 4 and 6, while the co-operating ratchet member if the lights are on, that is if the switch is closed, is at rest with the diametrical axis of its ratchet teeth 15 extending in a horizontal direction as indicated in Figure 5. It should be noted that the torsion spring not only imparts a torsional movement in a counterclockwise direction to the driving member of the ratchet couple to wind up the pull chain, but it also exerts an outward pressure on said driving member of the ratchet couple to press it yieldingly into engagement with the driven member 14 of the ratchet couple. Now with the parts in the position indicated in Figures 4 and 5, the teeth 17 lie between the two co-operating teeth 15 with the two plates pressed into close contact so that a rotation through a small arc brings the abrupt edges of teeth 17 against the abrupt shoulder of teeth 15, after which a continued rotation of the driving member 16 under the pull of the chain 9, serves to rotate the driven member 14 secured to the switch spindle through a sufficient arc, perhaps 90° or more, to throw the switch beyond its dead center, thereby shifting the switch from closed to open position.

Suppose, however, that the switch is already in open position in which case the teeth 15 will be in vertical relationship as shown in full lines in Figure 6. In such case the teeth 17 will have to travel through an arc several times as great as in the former case before operative engagement is established between said teeth 17 to operatively engage the shoulders of teeth 15. Now the device is adjusted in this particular case so that the movement of the actuating arm 22, from its limit when the door is open to its inward limit when the door is closed, produces a rotation of approximately half the circumference of the driving ratchet member, and so much of this entire arc of rotation is consumed in lost motion before operative engagement is established between the teeth 17 and the teeth 15 when the switch is closed or on, that insufficient rotation of the spindle is produced to turn the switch to or beyond its dead center. In such case, therefore, there is a small rotative movement of the switch spindle through the two engaged ratchet members which, however, does not result in throwing the switch. This differential rotation of the switch spindle, according to the initial position of the switch itself whether in off or on position, is vital to the proper functioning of the device.

Cases may arise where one may wish to leave the cellar door open while inside the cellar and desires to avoid having the light turned off by the closing of the door accidentally or otherwise. In such case, after

the door is open the latch 27 is thrown into engagement with the arm 22 which is shoved to proper position for that purpose and the friction induced by the tension of 5 the pull member 9 serves to keep these parts interlocked. If the door is closed, in such case the driving ratchet member will not have been rotated sufficiently to lie in position to throw the switch after the switch 10 has been turned on by hand and, consequently, does not throw the switch. Such closing of the door, however, will release the latch member so that when the door is next opened the arm is free to allow the 15 driving ratchet member to return to its normal initial position and function properly on the next closing of the door.

It will be seen that there is no interference whatever with the manual operation of 20 the switch whether the door be open or closed yet on leaving the room containing the switch the lights will be automatically cut off by the closing door, in case of oversight, while the open switch will not be 25 closed by the door in any case. The device may be temporarily held against action for a single occasion and thereafter restores itself to normal operation by one closing of the door or the connection between the flexible pull and the actuating 30 arm may be released by slackening the retaining screw 24, which connection however may be readily restored by again attaching the pull chain.

What I claim is:

1. A safety switch device embracing in combination, a snap switch of the intermittently rotatable spindle type including an insulating base, a hollow supporting member upon which said base is mounted, a rotatable chain drum mounted next said supporting member and having ratchet connection with the switch spindle to throw the switch, and a return spring for rewinding the chain on the drum, and a chain-pulling lever pivotally mounted in juxtaposition to the door to be actuated by

the pressure of the door to pull the chain and actuate the switch one step when the door is closed, substantially as described. 50

2. A safety switch device embracing in combination a snap switch of the intermittently rotatable spindle type having at its outer end a manual operating device and at its other end a ratchet-pull actuating member, a pivotal lever connected with said chain mounted to be actuated by engagement with the door when the same is closed to pull the chain and actuate the switch, and manually controlled means for locking the lever against moving in the reverse direction, substantially as described. 55

3. A safety switch device embracing in combination a switch-actuating lever pivotally mounted on the doorframe to be engaged and moved in switch-actuating direction by the closing door, a rotatable snap switch provided with a ratchet-pull chain connected to the opposite end of said lever to that engaged by the door, a gravity latch adapted to be moved by hand into engagement with said lever to prevent its reverse movement when the door is opened and to be disengaged by gravity the next time the door is closed, substantially as described. 65

4. In a safety switch the combination with a manually operable rotatable snap switch, of a ratchet pull device operatively connected with said switch to give it different arcs of rotation dependent upon the switch being in open or closed position, a pivoted arm located adjacent to a door to be actuated by the closing of the door combined with said ratchet pull to rotate the switch through the larger arc when the switch is in closed position and in the smaller arc when the switch is open, and means for temporarily preventing the arm from performing its normal operation by the closing 70 of the door, substantially as described. 75

In witness whereof, I have subscribed the above specification.
